Primary Examiner—Jeffrey Asch

(74) Attorney, Agent, or Firm—Banner & Witcoff, Ltd.

(57) **CLAIM**

The ornamental design for a keypad for a handset, as shown and described.

DESCRIPTION

FIG. 1 is a bottom plan view of a keypad for a handset showing our new design;

FIG. 2 is a right side view thereof;

FIG. 3 is a front view thereof;

FIG. 4 is a left side view thereof;

FIG. 5 is a top plan view thereof; and,

FIG. 6 is a perspective front view thereof.

The broken line showing of the remainder of the keypad is for illustrative purposes only and forms no part of the claimed design. The rear of the keypad forms no part of the claimed design.
